United States Patent

Des. 236,678
Patented Sept. 9, 1975

236,678

BARBECUE SPATULA

James A. Rader, Lamar, Mo., assignor to New World
Bar-B-Q Accessories, Inc., Lamar, Mo.

Filed May 2, 1974, Ser. No. 466,268

Term of patent 14 years

Int. Cl. D7—06

U.S. Cl. D7—105

FIG. 1 is a top perspective view of a barbecue spatula showing my new design;

FIG. 2 is an end view thereof as seen from the right in FIG. 1;

FIG. 3 is a side elevational view thereof; and

FIG. 4 is a bottom plan view thereof.

I claim:

The ornamental design for a barbecue spatula, as shown.
